**REEL SUPPORTING MECHANISM FOR USE
IN PRINTING MACHINES**

Cecil George Quick, Donald Arthur Ball, and Thomas Richard Bennett, London, England, assignors to Irving Trust Company, permanent trustee for R. Hee & Co., Inc., New York, N. Y., a corporation of New York

Application February 25, 1933, Serial No. 658,542
In Great Britain February 29, 1932

15 Claims. (Cl. 242—58)

This invention relates to improvements in roll supporting mechanism for use in supporting spindle-less rolls from which webs are drawn to printing machines.

5 The main object of the present invention is to provide an arrangement in which economy in space, both horizontally and vertically can be effected in trucking rolls to a support in a printing machine.

10 The preferred embodiment of the invention is illustrated in the accompanying drawings, wherein:

Figure 1 is an elevational view of the roll supporting mechanism as applied to a printing machine:

19 Figure 2 is a side elevational view of Figure 1;
Figure 3 is an enlarged detail view showing a
mounting for one end of an operating shaft and
a clutch member cooperating therewith shown
20 in section; and

Figure 4 is an end elevational view of Figure 3. Referring to the drawings there is provided on each side of front and rear vertical standards 1, 2 (which may form part of the frame of the printing machine) a pair of arms 3, 4 (hereinafter referred to as the "front" and "rear" arms respectively), each arm being provided in a manner which is well known, with plugs adapt-

30 ed to enter the central or core diameter of the spindle-less rolls. As each pair of arms is identical and is associated with identical mechanism, reference will, in the description hereafter, be directed to one of the pairs of arms only. The

35 front arm 3 is movable from the position shown for the mechanism at the right hand side of the support 1 to a position (indicated for the mechanism at the left hand side of Figure 2) such

40 that the roll can be "trucked" into position on the plug on the rear arm 4 whereafter the arm 3 can be lowered and its plug caused to enter the roll. In order to effect this, the arms 3 and

4 are mounted upon a traverse shaft 5 which is mounted in journals 6 located near the base of the standards 1, 2 the rear arm 4 being secured 45 against relative angular movement with respect

to the shaft while the front arm 3 is freely mounted on the shaft 5 and is connected to the shaft through a lost-motion device which while enabling the arm 3 to move angularly with re-

50 spect to the shaft and to be swung up to permit trucking to be effected also enables the shaft 5 to move both arms simultaneously to raise the roll clear of the truck very slightly. The lost-motion device comprises a third arm 7 which is 55 carried on the shaft so as to be held against

relative angular movement with respect thereto, and a link 8 which is pivotally connected at 9 to the front arm 3 and is provided at its upper end with a slot 10 into which extends a pin 11 on the third arm 7, the slot having a short portion 10' at right angles to the principal part so that the arm 7 is latched to the link 8 in a definite position; thus, while the front arm 3 can be moved upwardly with respect to the third arm 7 (and hence with regard to the shaft 5 and the rear arm 4) when the third arm and consequently the rear arm 4 are rocked by movement of the shaft 5, the link 8 transmits the similar movement to the front arm 3. The raising of the arms 3, 4 may be effected by a windlass arrangement comprising a cable 12 which is wrapped around a two diameter drum 13 secured to an operating shaft 14, and a loop in the cable is passed over a pulley 15 mounted on an arm 16 secured to the shaft 5: the arrangement thus provides a differential pulley block reduction gear which obviously could be replaced by any other type of gear for providing a mechanical advantage of an operating member over the shaft 5. Such a modified kind of gear could comprise a gear wheel reduction gear interposed between a one diameter cable pulley and an operating shaft therefor.

The shaft 14 is provided with a handle 17 located at the front of the machine and in order to ensure that damage shall not be done to the mechanism by an operator allowing the arms to move downwardly under their own weight and that of the roll without restraint, the arrangement for effecting lowering of the arms is such that the operating handle has to be moved continuously so long as movement is required and that if the operating handle ceases to be operated, the arms will come to rest substantially simultaneously. This is effected by connecting the handle 17 to the shaft 14 through a lost-motion arrangement comprising a lug 18 on a sleeve 19 to which the handle 17 is connected and a slot 20' formed in a disc 20 secured to the shaft 14. The sleeve 19 is internally screw threaded and engages a screw thread 21 formed on a sleeve 22 which is secured to the shaft 14 and this sleeve 22 carries one part 23 of a friction disc clutch whose other part 24 is mounted on the sleeve 22, and abuts against the end of the sleeve 19, a slight axial movement of the sleeve 19 and of the part 24 being permitted on the sleeve 22. The part 24 of the clutch is provided on its periphery with ratchet teeth 25 engaged by a pawl 26 pivotally mounted at 27 on the standard. 30 35 40 45 50 55

The hand of the screw thread is such that the weight of the arms 3-4 and their associated parts and of the roll, causes the sleeve 19 to press the part 24 against the part 23 of the clutch. As the part 24 is held by the pawl 26 against rotation in a direction corresponding to downward movement of the arms, it follows that through the clutch 23, 24, the pawl 26 holds the arms in the position to which they are moved.

10 If now it is desired to lower the arms, the handle 17 is rotated in such a direction as to cause the sleeve 19 to be moved by the screw thread 21 away from the part 24 of the clutch, this rotation of the sleeve 19 with respect to the sleeve 22 being permitted by the lost-motion arrangement 18, 20'. The clutch is now disconnected and the arms 3, 4 are freed from restraint by the pawl and can lower under their weight and will continue to do so so long as the handle is moved 15 to maintain the sleeve 19 in that position relatively to the sleeve 22 to which it is moved by the initial movement of the handle. As soon, however, as motion of the handle ceases, the sleeve 22 will regain the lost-motion (i. e. will move relatively to the sleeve 19) and thus the screw thread will act in the opposite direction and force the part 24 of the clutch against the part 23 and thereby bring the arms to rest. It 20 will of course be apparent that when the handle 25 is moved to raise the arms, the pawl 26 will act as a detent to sustain the weight of the arms. The handle 17 is preferably formed separately from the sleeve 19, and to provide for the drive connection, the handle is formed with lugs 28 30 which can enter recesses 29 formed in a flange 19' on the sleeve 19, the handle being bored to fit over the sleeve.

Tension of the web 30 passing from the roll is controlled by bands 31 secured at their ends to 40 frames 32 which are pivotally mounted on a shaft 33 journaled in the standards 1, 2. The bands are preferably connected to the frames at one end (or at both ends) through levers 34 which are loaded by springs 35 which place the bands under an adjustable initial tension and preferably also the frames are weighted by adjustable weights 36 mounted on arms 36' fast on the shaft 33.

It will be understood that when the arrangement described above is duplicated, one roll 50 would be the running roll (i. e. the one in use) while the other would be the spare roll and could be trucked into position in readiness to become the running roll in its turn while the existing running roll is feeding.

The plugs on the front and rear arms are arranged to be moved axially into and out of position in any usual way as by means of gearing indicated at 37 and moreover to enable rolls of 60 different widths to be supported, the front, rear and third arms are adjustable longitudinally of the supporting shaft and are provided with clamping bolts to enable the arms to be clamped in any desired position.

65 In order to provide for adjustment of side lay of a roll supported in the arms, the shafts 5 are slidably mounted in the bearings at one end and the other ends of the shafts are interconnected by a yoke piece 38 which is adjustable by a screw threaded member 39 having an operating hand wheel 40.

It will be seen that with the arrangement according to the invention, considerable economy in space can be effected since the rolls can be 75 trucked in in a space equal only to that occupied

by the roll when in use, i. e. space is not required to enable the roll to be trucked in at the side of its normal running position, the roll thereafter being moved laterally with respect to its length into normal or running position. Moreover, the whole operation of web replenishing can be effected from one side of the machine, a feature which is of importance both from the question of time saving and also of installation where this is effected closely adjacent a wall. 10

What we claim is:—

1. In web roll supporting mechanism, the combination of a pair of pivotally mounted arms adapted conjointly to support a web roll between them, a member common to the two arms for effecting simultaneous angular movement thereof, and means to permit one arm to be rocked independently of the other arm and into position to permit a roll to be moved endwise into position to be supported by the arms. 20

2. A web roll supporting mechanism for use with a printing machine, comprising a pair of members which are adapted conjointly to support a web roll between them, means to effect a simultaneous rocking movement of the two support members, and means to permit one support member to be rocked independently of the other, whereby a roll may be moved endwise into a mounting position. 25

3. A web roll supporting mechanism for use with a printing machine, comprising a pair of members which are adapted conjointly to support a web roll between them, means to effect a simultaneous rocking movement of the two support members through an operating source, and a connection to release one of said support members from the operating source, whereby said latter support member may be rocked independently of the other to permit a roll to be inserted endwise into a mounting position. 30

4. A web roll supporting mechanism for use with a printing machine, comprising a pair of arms angularly movable about a common axis, operating means to rock said arms simultaneously, and a connection whereby one of said arms may be rocked independently to permit the endwise insertion of a web roll to a mounting position. 45

5. A web roll supporting mechanism for use with a printing machine, comprising a pair of arms angularly movable about a common axis, a third arm also movable therewith, means to rock the third arm and one of the first mentioned arms simultaneously, and a link connecting the third arm with the other of the first mentioned arms and having a connection whereby said latter arm 50 is adapted to be disconnected from the third arm to permit independent movement thereof, whereby the same may be rocked so as to permit the endwise insertion of a web roll to a mounting position. 55

6. A web roll supporting mechanism for use with a printing machine, comprising a pair of web roll supporting arms, a shaft upon which said arms are mounted, one being fixed thereon and one being freely movable thereon, a third arm also fixed to the shaft, and a link having a lost motion slot therein joined to the freely movable arm which, link is adapted to connect the freely movable arm in a driving relation with the third arm, to move the web roll supporting arms simultaneously and is adapted to be disconnected from its driving relation through its lost motion slot to permit the freely movable arm to be moved freely around the shaft to a position which will clear a web roll when moving same endwise to a loading position. 60

7. A web roll supporting mechanism for use with a printing machine, comprising a pair of web roll supporting arms mounted on a shaft, one arm being freely mounted and the other being fixed to the shaft, operating means for effecting rocking of the shaft, and means connecting the freely mounted arm to the shaft in such manner that when the shaft is rocked the latter arm can be moved simultaneously with the fixed arm to effect raising of a roll supported between them, while the freely mounted arm can be swung to a position to enable a roll to be moved endwise into a position for mounting upon the arms. 5
8. A mechanism as defined in claim 7 in which the connecting means for the freely mounted arm comprises an additional arm mounted on the shaft and is prevented from rocking with respect thereto, and a link which is pivotally connected to one of these arms and has a pin and slot connection 10 with the freely mounted arm. 15
9. A web roll supporting mechanism for use with a printing machine, comprising a pair of pivotally mounted members which are adapted conjointly to support a web roll between them, operating means to effect a simultaneous rocking movement of the arms to cause the raising of a roll supported by the arms, means for automatically holding the roll supporting arms in the position moved to by the operating means, 20 and means to permit one arm to be swung relatively to the other to permit a web roll to be moved endwise into a mounting position. 25
10. A web roll supporting mechanism for use with a printing machine, comprising a pair of pivotally mounted arms which are adapted conjointly to support a web roll between them, operating means to effect a simultaneous rocking movement of the arms including a rotatable member having a clutch cooperating therewith 30 to hold the roll supporting arms in the position moved to by the operating means, means to cause said clutch to be released by the movement of the operating means when the operating means is moved to rock the arms and to engage said clutch to prevent further movement of the arms 35 when the operating means ceases to function. 40
11. A web roll supporting mechanism for use with a printing machine, comprising a pair of pivotally mounted members which are adapted conjointly to support a web roll between them, operating means to effect a simultaneous rocking movement of the arms to cause the raising of a roll supported by the arms, including a shaft in operative connection with the arms and 45 having an externally screw threaded member mounted thereon, an internally screw threaded sleeve connected to an operating member and engaging the externally screw threaded member, said sleeve having a lost motion slot therein, and a plate fixed at one end thereof, a second plate positioned over said sleeve and adapted to be held in frictional relation with the first named plate when the operating member is not being moved, and a means for holding the second plate 50 fixed against rotation in one direction. 55
12. A mechanism as defined in claim 11 in which the means for holding the second friction plate fixed against rotation in one direction comprises a pawl mounted on the machine frame and engageable with a ratchet toothed periphery on the second plate. 15
13. A web roll supporting mechanism for use with a printing machine, comprising a pair of pivotally mounted arms which are adapted conjointly to support a web roll between them, means to permit one arm to be rocked independently of the other, operating means to effect a simultaneous rocking movement of the arms to cause the raising of a roll supported by the arms, and 20 a reduction mechanism cooperating with said operating means. 25
14. A web roll supporting mechanism for use with a printing machine, comprising a pair of arms pivotally mounted on a shaft and adapted to support a web roll, means for rotating said shaft to rock the roll supporting arms, one of said arms being movable independently of the shaft movement to provide for an endwise insertion of a web roll to a mounting position, and 30 means to laterally adjust said shaft. 35
15. A web roll supporting mechanism for use with a printing machine, comprising a pair of pivotally mounted arms which are adapted to conjointly support a web roll between them, operating means to effect a simultaneous rocking movement of the arms to cause the raising of a roll supported by the arms, and a reduction mechanism cooperating with said operating means including a cable mounted on a differential drum, a member movable with one roll supporting arm and having a pulley thereon, which pulley is engaged by the cable and is adapted to cooperate in raising or lowering the roll supporting arms when the differential drum is rotated. 40 45 50
